UNITED STATES PATENT OFFICE.

JOHN M. RAUHOFF, OF CHICAGO, ILLINOIS, ASSIGNOR OF NINE-TWENTIETHS
TO EDWARD TROYER, OF SAME PLACE.

SOAP HOLDER AND DISTRIBUTER.

SPECIFICATION forming part of Letters Patent No. 635,592, dated October 24, 1899.

Application filed November 14, 1898. Serial No. 696,440. (No model.)

To all whom it may concern:

Be it known that I, JOHN M. RAUHOFF, a citizen of the United States, residing at Chicago, Illinois, have invented certain new and 5 useful Improvements in Soap Holders and Distributers, of which the following is a specification.

The object of my invention is to make a device in which soap can be held and easily 10 and readily conveyed or distributed to the hands, in which the soap cannot be readily removed, and in which all of the soap may be consumed and utilized; and my invention consists in the features and details of construction 15 hereinafter described and claimed.

In the drawings, Figure 1 is a vertical section of my improved soap holder and distributor; Fig. 2, a vertical section of a modified form of the same, and Fig. 3 a plan view of 20 still another modified form.

In making my improved soap holder and distributor, as described in Fig. 1, I make a can, tube, or box A of a desired size and height and preferably mount it on a base B, 25 which may be fastened or attached by screws or otherwise to a table or washstand. If preferred, however, the base and the can, tube, or box may be made integral and spun or otherwise formed into the desired shape.

Within the can, tube, or box I arrange a soap-cup C, which may be formed of tin, glass, porcelain, or other suitable material. This soap-cup is preferably provided with a downwardly-projecting flange c around its edges 35 to enable it to fit well and true within the can, tube, or box A. It is made cup-shaped

at the top, so that a ball or sphere may fit into it, and it is preferably provided at its bottom with a downwardly-projecting neck c', around which a spring C' may be arranged 40 to constantly move the soap-cup up and hold it in the highest position permitted. The cup is provided with soap D, as shown in Fig. 1, and a ball or sphere E, of rubber, glass, metal, 45 or other suitable material, is arranged in the can, tube, or box so that its lower side or surface rests upon and is embedded in or surrounded by the soap. The top of the can, tube, or box is preferably turned in, as at a,

50 so as to prevent the ball or tube from being readily withdrawn or removed when arranged

in place. The ball, however, is permitted to turn or roll freely, so that when a person wets his hand and rubs it over the surface of the ball it will be caused to roll or turn, and thus 55 bring up to his hand a thin sheet or coating of soap sufficient for the purpose. Of course as much as desired may be obtained by rubbing the hands over the ball and causing it to roll in contact with the soap. As the soap 60 is fed to the hand it is distributed in a thin layer, so that no more is absorbed by the hands than is necessary or desired. As the soap is consumed or exhausted by use the spring constantly moves the soap-cup upward 65 and keeps it in contact with the ball or sphere, so that the soap is supplied until the entire amount in the cup is consumed or exhausted. In this way no loss or waste of soap is suffered, as it may all be used and consumed. 70

In Fig. 2 I have shown the same idea, but have made the tube, can, or box A and the soap-cup C of one integral piece, as will be readily understood from an examination of the drawings. I have further provided it 75 with a cover or cap F, which may be slid on over the ball or sphere, so as to protect the same from dust when there is no occasion for its use.

In Fig. 3 I have shown still another modification of my soap holder and distributor. In this case the can, tube, or box A is made rectangular, and the soap-distributer E instead of being a ball or sphere is made in the form of a cylinder or roll G. This will be 85 readily understood from an inspection of the drawings.

In all the above cases it will be seen that the hand does not come in contact with the soap, but that there is interposed between 90 the hand and the soap a distributor which is capable of being rotated or turned by rubbing the hand over the same, so that it brings up and supplies the soap to the hand in a thin layer or distributed condition in order that 95 all of the soap may be consumed and none of it wasted or lost.

I claim—

1. A soap carrier and distributor comprising a cup or receiver for the soap, and a rotatable body or carrier entered into the open end of the cup or receiver, between which and

the closed end of the cup or receiver soap may be interposed, whereby the turning of the rotatable body or carrier by hand takes up and transfers a quantity of soap for use, substantially as described.

2. A soap carrier and distributer comprising a cup or receiver for the soap, and a rotatable body or carrier entered and loosely supported in the open end of the cup or receiver, between which and the closed end of the cup or receiver soap may be interposed, whereby the turning of the rotatable body or carrier by hand takes up and transfers a quantity of soap for use, substantially as described.

3. A soap carrier and distributer comprising a stand or holder, a cup or receiver located in the stand or holder, and a rotatable body or carrier entered into the open end of the cup or receiver, between which and the closed end of the cup or receiver soap may be

interposed, whereby the turning of the rotatable body or carrier by hand takes up and transfers to the hands of the user a quantity of soap, substantially as described.

25

4. A soap carrier and distributer comprising a cup or receiver for the soap, a rotatable body or carrier entering the open end of the cup or receiver in contact with soap interposed between it and the closed end of the cup or receiver, and means for automatically advancing the soap against the rotatable body or carrier as it wears away, whereby the rotatable body or carrier will constantly engage the soap and take up and transfer a quantity thereof to the hands of the user, substantially as described.

JOHN M. RAUHOFF.
